UNITED STATES PATENT OFFICE

2,431,097

ELECTRON DISCHARGE DEVICE

Karel van Gessel, Scarsdale, N. Y., assignor, by
mesne assignments, to Philips Laboratories,
Inc., Irvington-on-Hudson, N. Y., a corporation
of Delaware

Application September 8, 1944, Serial No. 553,212

10 Claims. (Cl. 250—27.5)

1

This invention relates to electron discharge devices, and more particularly to fluid cooled electrodes for such devices.

An object of the invention is to provide fluid cooled electrodes with improved heat transfer characteristics.

Another object of the invention is to provide fluid cooled electrodes of simplified construction.

A further object of the invention is to provide fluid cooled electrodes which are mounted in and sealed to the envelope in a simple, inexpensive manner.

Still another object of the invention is to provide structures of the type aforesaid wherein the electrodes are electrically insulated from the cooling fluid.

Other objects, and the manner in which the same are attained, will appear from the following description.

In the drawing accompanying this specification and forming part thereof two embodiments of the invention are illustrated diagrammatically by way of example.

In the drawing,

Fig. 1 shows a diagrammatic side view of one embodiment of the invention, and

Fig. 2 is a diagrammatic side view, shown in perspective, of another embodiment of the invention.

Referring now to the drawing wherein corresponding parts are denoted by identical reference numerals, and first to Fig. 1, 1 is the envelope of an electron discharge tube and 2 is the cathode and 3 the grid forming part of the electrode assembly of the tube.

U-shaped tubing 4 of glass or gas-impervious metal, for example, serving as passage for a cooling medium and having an inlet 5 and an outlet 6, is mounted in and sealed to, the bottom 7 of envelope 1 and extends into the interior of the envelope so as to surround the grid 3.

In accordance with one of the basic concepts of the invention, the tubing 4 is provided, for example by plating or coating, with cylindrical anode portions 8 which are arranged opposite two sides of the grid 3 and which extend over a distance corresponding substantially to the effective electron-emitting portion of the cathode 2. In the case of either glass or metal tubing, the anode portions 8 may be provided by coating the tubing with zirconium; if the tubing is made of glass some other suitable metal may be initially plated or otherwise deposited thereon. The anode portions 8 are interconnected by a wire 9, as shown in Fig. 1.

2

In the operation of the electron discharge tube according to Fig. 1, cooling fluid such as water enters the inlet 5; traverses the tubing 4 so as to cool the anode portions 8 over the entire area thereof, and leaves by the outlet 6.

The intimate contact of the cooling medium with the base of the anode, over the entire surface of the latter, results in optimum heat transfer characteristics. If the tubing is made of glass or the like, the anode portions are insulated from the cooling medium by the agency of the glass or other insulating material separating the metallic anode portions from the cooling fluid. Other important advantages of the electron discharge tube according to Fig. 1 involve simplicity of construction and assembly, and a corresponding lowering of the cost of manufacturing the tube.

Another embodiment of the invention is illustrated in Fig. 2. The envelope 1 and that part of the electrode assembly including the cathode 2 and the grid 3 correspond to the showing of Fig. 1. U-shaped tubing 11 made of gas-impervious metal or glass, for example, and having an inlet 12 and an outlet 13, is mounted in and sealed, for example by fusing, to the bottom 14 of the envelope, and extends into the interior of the envelope so as to surround the grid 3.

In accordance with another fundamental concept of the invention, the tubing 11 mounts semi-circular, flattened, hollow anode portions which surround the grid 3 and extend over a distance substantially corresponding to the effective electron-emitting portion of the cathode 2.

These hollow anode portions 15 may be made of glass and may have a layer 16 of zirconium deposited on them, as shown in Fig. 2, or in case the tubing 11 is made of metal, these anode portions may be made of a gas-impervious metal preferably covered with zirconium. The portions 15 are conductively interconnected by the tubing 11 in case this is made of metal, or else by a connecting wire as shown in Fig. 1.

In the operation of the embodiment of the invention according to Fig. 2, cooling medium enters the inlet 12; traverses the tubing 11 and hollow anode portions 15 so as to be in intimate heat-transferring contact with substantially the entire surface of these anode portions; and leaves by the outlet 13.

The electron discharge tube according to Fig. 2 involves numerous advantages such as simplicity of construction and assembly, low cost, ruggedness and most important, excellent heat-

transfer characteristics resulting in dependable cooling of the anode portions.

I wish it to be understood that I do not desire to be limited to the details of construction, design and operation shown and described as various modifications within the scope of the appended claims may occur to a person skilled in the art.

I claim:

1. An electron discharge device, comprising an envelope, a bottom in said envelope, electrodes including a cathode and a grid mounted in said bottom, a U-shaped tubular cooling member of insulating material mounted in said bottom so as to surround said electrodes, and metallic anode portions plated on the legs of the U-shaped member.

2. An electron discharge device, comprising an envelope, a bottom in said envelope, electrodes including a cathode and a grid mounted on said bottom, a U-shaped tubular cooling member of glass mounted in said bottom so as to surround said electrodes, and metallic anode portions plated on the legs of the U-shaped member and extending over a distance corresponding substantially to the effective electron emitting portion of said cathode.

3. An electron discharge device, comprising an envelope, a bottom in said envelope, electrodes including a cathode and a grid mounted on said bottom, a U-shaped tubular cooling member of insulating material mounted in said bottom so as to surround said electrode, and flattened hollow anode portions in the legs of said U-shaped member, said anode portions comprising zirconium coatings forming the surfaces thereof.

4. An electron discharge device, comprising an envelope, a bottom in said envelope, electrodes including a cathode and a grid mounted on said bottom, a U-shaped tubular cooling member of insulating material mounted in said bottom so as to surround said electrodes, flattened hollow anode portions in the legs of said U-shaped member, and a zirconium coating on said anode portions forming the surfaces thereof.

5. An electron discharge device, comprising an envelope, a bottom in said envelope, electrodes including a cathode and a grid mounted on said bottom, a U-shaped tubular cooling member of insulating material mounted in said bottom so as to surround said electrodes, flattened hollow anode portions in the legs of said U-shaped

member, and a zirconium coating on said anode portions.

6. An electron discharge device, comprising an envelope, a bottom in said envelope, a U-shaped tubular cooling member of insulating material mounted in said bottom, zirconium plated anode portions on the legs of said U-shaped member, and the remaining electrodes mounted on said bottom between the legs of said U-shaped member and in alignment with said anode portions.

7. An electron discharge device, comprising an evacuated envelope, glass conduit means for circulating a cooling medium mounted in said envelope, and a zirconium electrode in the form of a plating on said conduit means.

8. An electron discharge device comprising an evacuated envelope, glass conduit means for circulating a cooling medium mounted in said envelope, a cathode and a grid mounted in said envelope and a zirconium anode in the form of a coating on said conduit means in proximity to said grid.

9. An electron discharge device, comprising an evacuated envelope, and a conduit of insulating material mounted in said envelope for circulating a coolant and having metallic anode portions plated thereon.

10. An electron discharge device, comprising an evacuated envelope, and a conduit of insulating material mounted in said envelope for circulating a coolant and having zirconium anode portions plated thereon.
